(57) **CLAIM**

The ornamental design for a dispenser, as shown and described.

DESCRIPTION

FIG. 1 is a top, front, and right side isometric view of an ornamental design for a dispenser;

FIG. 2 is a top plan view of the dispenser of FIG. 1;
FIG. 3 is a front elevational view of the dispenser of FIG. 1;
FIG. 4 is a rear elevational view of the dispenser of FIG. 1;
FIG. 5 is a left side elevational view of the dispenser of FIG. 1; and,

FIG. 6 is a right side elevational view of the dispenser of FIG. 1.

The dash-dash-dash lines are included for the purpose of illustrating portions of the dispenser that form no part of the claimed design.

1 Claim, 4 Drawing Sheets
